SHEET DELIVERY MECHANISM

Arthur B. Woodruff, Brecksville, Ohio, assignor
to Harris-Seybold Company, a corporation of
Delaware

Continuation of application Serial No. 412,390,
September 26, 1941. This application June 13,
1945, Serial No. 599,151

5 Claims. (Cl. 271—79)

1

In the operation of printing presses equipped with mechanism for accumulating the sheets in a pile at the delivery end of the machine, it is usually necessary to shut the press down while the platform carrying an accumulated pile of sheets is removed, an empty platform is inserted and the automatic piling and platform lowering devices are adjusted to begin the stacking of a new pile.

With the advent of modern high speed rotary presses the frequency with which the operation has to be performed and the loss of production for a given length of shut down time has increased. Furthermore when thick stock such as cardboard is being printed changes are still more frequent and the loss is thus further accentuated.

Various solutions to this problem have been proposed. For example, presses have been equipped with two full sized pile delivery mechanisms placed in line and equipped with controls permitting the depositing of sheets on either platform while the other with its pile of sheets is being removed and replaced by an empty platform. This arrangement is objectionable because of the large amount of floor space required and the high cost of constructing what amounts to two complete delivery mechanisms.

In another arrangement a temporary platform is inserted above the accumulated pile in position to receive a relatively small number of sheets while the main platform is being changed, the temporary platform then being withdrawn leaving its pile of sheets on the main platform. This arrangement has not been satisfactory because of the difficulty of inserting and removing the temporary platform quickly while the machine is running and because the mechanism required interferes with convenient operation of the main pile mechanism.

It is an object of this invention to provide a delivery arrangement for a printing press or other machine which will permit continuous operation of the machine and will be free of the above disadvantages and convenient and efficient in operation.

Another object is to provide delivery means for a printing press which will provide two selectively operable sheet delivery mechanisms in the same floor space as is ordinarily required for a press having only one such mechanism.

Another object is to provide a printing press wherein the space between the main sheet delivery and the nearest printing unit is utilized both as a working space and as a space for the

2

accumulation of sheets while the main delivery platform is being removed and replaced.

Another object is to provide an auxiliary sheet delivery device for a printing press which can be placed into and out of operation quickly and efficiently while the press is running.

The invention has been illustrated in connection with a rotary offset lithographic printing press. In the figures

10 Fig. 1 is a side elevation view of a part of a lithographic press constructed according to the invention.

Fig. 2 is an enlarged view of a part of Fig. 1 showing the auxiliary delivery mechanism in greater detail, the parts being in position to cause sheets to be deposited on the auxiliary platform.

Fig. 3 is a view similar to Fig. 2 but showing the parts in position to permit the sheets to be conveyed to the main delivery platform.

20 Fig. 4 is a plan view of the auxiliary delivery mechanism corresponding to Figs. 1 and 2.

Referring to the drawings, 10 is the base of a printing press resting on the floor. Side frames 11, 12, which are secured to base 10 support a lithographic printing unit comprising impression cylinder 13, blanket cylinder 14, plate cylinder 15, form inking rollers 16, and dampening rollers 17. Impression cylinder 13 is equipped with sheet grippers 18 which are arranged and operated to open and close at proper times in known manner. Sheets are fed to impression cylinder 13 by a transfer cylinder 19 which receives them from any suitable source such as a preceding printing unit if the press is a multicolor press. It is to be understood, however, that the cylinders 13, 14, 15 may be the cylinders of a single color press, in which case cylinder 13 would receive sheets from suitable sheet feeding mechanism.

Frames 11, 12 also support a driven shaft 20 to which are keyed two sprockets 21, one at each side of the press, which drive a sheet delivery conveyor, later described, in the usual manner known in printing presses. Driving means of any known or preferred kind, not shown, are provided for rotating the cylinders in the directions indicated and for rotating shaft 20 for driving the conveyor.

The main pile delivery mechanism is supported by lower delivery side frames 22, 23, upper delivery side frames 24, 25, and legs 26, 27, all of which parts are secured to each other and to cross support members, not shown, in known manner to form a rigid supporting framework.

This main delivery mechanism is spaced from the printing unit previously mentioned by a dis-

tance suitable to provide the working space which is required at times by the operator in performing his duties incident to operation of the press, and to provide space for the auxiliary pile delivery mechanism subsequently to be described. Delivery frames 22, 23 are joined to and spaced properly from press frames 11, 12 by coupling frame members 28, 29 secured to the delivery frame by bolts 30 and to the press frames by bolts 31 and tie rod 32.

Frame members 28, 29 are formed with upward projections 33 which serve to support a work platform 34 having angle iron cleats 35. The platform 34 extends across the press between frames and is arranged at such height that the operator may conveniently reach the parts of the printing unit such as the inking mechanism, the plate cylinder 15, and blanket cylinder 14, which he must work upon during operation of the press.

The conveyor by which sheets are conveyed from impression cylinder 13 to the main pile delivery mechanism comprises a pair of endless parallel chains 36, 37, which support at intervals corresponding to the circumference of cylinder 13 a plurality of sets of grippers 38 (Fig. 1) for grasping the forward edges of the sheets. Each of these sets of grippers comprises a plurality of fingers 39 which are supported upon an oscillatable shaft 40 and a like number of abutments 41 carried by a fixed shaft 42. The shafts 40 and 42 are supported at their ends by brackets 43 each of which is supported at two points by the corresponding chain 36 or 37. Spring means, not shown, are provided tending to turn shaft 40 in the direction to close fingers 39 on their abutments. Keyed to shaft 40 is a lever 44 which carries a cam follower roller 45 for the purpose of opening the gripper fingers 39 against the aforementioned spring means.

The chains 36, 37 carrying the sets of grippers just described travel around sprockets 21, thence around sprockets 46, 47 suitably supported by frames 22, 23 thence around sprockets or wheels 48 which are supported on a shaft 49 fixed in frames 24, 25. In traveling back toward the press these chains pass around idler wheels 50 and 51 which are suitably supported on studs in frames 22, 23. Along the lower run of chains 36, 37 tracks 52, 53 are provided along the upper edges of which the chains run. These tracks are secured to frames 11, 12 by brackets 54 and to frames 22, 23 by brackets 55. Other tracks, not shown, are provided where needed to support the chains.

Mechanism of known construction is provided for causing the sheets to be released by the sets of grippers 38 and to be deposited in the form of a relatively high main pile of sheets 56. Such mechanism comprises a bracket 57 supported upon tie rod 58 and shaft 49 and carrying a gripper opening cam 59 located in proper position to engage each of the rollers 45 associated with the traveling sets of grippers. Cam 59 functions to open gripper fingers 39 at the proper time to cause the sheets to drop on pile 56. This action is facilitated by the usual stripper fingers 60 and end stakes 61.

The pile 56 is formed upon a main delivery platform 62 which is provided with legs 63 and is supported on cross beams 64 extending across the press and resting at their ends upon lift bars 65. Each of the latter bars is raised and lowered by a pair of cables 66, 67 having hooks 68 at their lower ends for engaging pins 69 in the bars

65. The rear cables 66 extend upward, around sheaves 70, then toward the press and around sheaves 71 and downward to drums 72 keyed to the automatic power driven pile lowering shaft 73 journaled in frames 22, 23. The front cables 67 extend upward and partly around sheaves 71 and thence downward and around drums 72. Known means not shown are provided for automatically gradually rotating shaft 73 to cause platform 62 to lower at the proper rate to accommodate the accumulation of sheets in the pile 56. Further description is deemed unnecessary since such mechanism is well known in the art.

15 It is to be noted that the various parts, including the printing unit, the press frames, delivery frames, coupling members 28, 29, platform 34, and the sheet conveyor supports have been so arranged as to provide a space below the lower run of the conveyor and between the press and delivery frames. In this space an auxiliary delivery platform 74 is provided for receiving sheets from the conveyor during the time a full main platform 62 is being removed and replaced by an empty platform, thus allowing continuous operation of the press.

20 Auxiliary platform 74 is equipped with four wheels or casters 75 carried in brackets 76 secured to the platform and the casters 75 are guided between rails 77 bolted to the floor. Platform 74 is provided with side wall members 78, 79 supported on brackets 80, 81 which may be adjusted to accommodate different widths of sheets by sliding the same along grooves 82 and clamping by means of thumb screws 83. Each 25 of the side wall members 78, 79 has adjustably clamped thereto an end wall member 84 supported by an iron brace 85 one portion of which slides in a groove 86 in the corresponding side wall member 78 or 79. Brace 85 also has integral 30 therewith a threaded stud 87 which extends through slot 88 and carries a wing nut 89 for tightening the members 84 in various positions to accommodate sheets of different lengths.

35 Platform 74 is arranged to occupy a position adjacent to a vertical plate 90 having cleats 91 which are fastened at their lower ends to a square cross bar 92 secured by bolts 93 in frames 22 and 23 and at their upper ends to brackets 94 which loosely embrace a shaft 95 rotatably journaled 40 in the delivery side frames 22, 23. Plate 90 forms an end wall for the platform 74 when the latter is in operative position and, in conjunction with side wall members 78, 79 and end wall members 84, forms a box like structure for receiving sheets and forming them into a pile as 45 they are deposited by the sheet conveyor.

To selectively control the deposition of sheets on the platform 74 mechanism is provided which will now be described. Below the delivery conveyor drive shaft 20 is a cross support bar 96 secured by bolts 97 to frames 11, 12. This bar has a pair of brackets 98 secured thereto by bolts 99 and these brackets carry a rotatable shaft 100 and a non-rotatable round bar 101. On shaft 100 are keyed two tape drums 102 each carrying a pin 103 to which one end of a torsion spring 104 is secured, the other end of the spring being secured to a pin 105 in bracket 98. Additional tape drums in any desired number are also provided, of which one is shown at 106. Springs 104 are arranged to tend to turn shaft 100 in the counter-clockwise direction as viewed in Fig. 1.

50 Each of the drums 102, 106 has secured thereto one end of a tape 107 of suitable length which is 55 trained partly around bar 101 and thence toward

the delivery platforms to a bodily movable square cross bar 108 to which it is fastened by screw 109. The ends of bar 108 are turned down to form necks 110 which slidably fit into slots 111 in guide bars 112 one of which is fastened to chain track 52 and one to track 53 by bolts 113. Near each end of bar 108 is a hole through which extends a cable 114 having an enlarged end 115 which prevents the cable from passing through the hole in one direction. These cables extend toward the left in the figures, pass partly around grooved idler wheels 116 on shaft 95 and thence around grooved winding drums 117 to which the ends of the cables are attached.

The drums 117 are keyed to a shaft 118 which is rotatably journaled in frames 22, 23 and is held against endwise movement by collar 119 and a small gear 120 keyed to the shaft. The hub of each of the drums 117 carries a pin 122 to which is secured one end of a torsion spring 123 surrounding shaft 118, the other end of the spring being secured to a pin 124 in the corresponding frame 22 or 23. The action of the springs 123 is to tend to rotate shaft 118 counterclockwise as viewed in Figs. 1 to 3 thus tending to wind cables 114 around drums 117.

On the outside of frame 22 a bracket 125 is fastened to the frame by bolts 126. This bracket supports a rotatable stub shaft 127 to the inner end of which is keyed a large gear 128 whose teeth mesh with the small gear 120 secured to shaft 118. To the outer end of stub shaft 127 is keyed a lever 129 to which is pivotally connected one end of a link 130 whose other end extends through a pin 131 pivotally mounted in hand lever 132. Nuts 133 are provided to adjustably secure link 130 to pin 131 and lever 132 is provided with a handle 134.

Lever 132 is keyed to a shaft 135 which is rotatably journaled in frames 22, 23 and has secured thereto a bifurcated lever 136 which pivotally carries between its bifurcations on pin 137 a link 138. Lever 136 is formed with a projecting abutment 139 which is adapted to engage abutment 140 of link 138 to limit movement of the lever 136 and shaft 135 in one direction when lever 136 and link 138 are substantially in alignment with each other.

The other end of link 138 is provided with a rotatable stud 141 having a shoulder portion 142 and a reduced extension 143 which extends through slot 144 in a bracket 145 which is pivotally mounted on tie rod 146 supported in frames 22, 23. Extension 143 of pin 141 is threaded and carries a washer 147 and clamping nut 148 by which bracket 145 is clamped against shoulder 142 of pin 141. By means of the slot and clamping arrangement just described the operative position of bracket 145 may be adjusted to suit conditions. A cam 149 is secured to bracket 145 by screws 150 and the parts are so arranged that cam 149 lies in the path of travel of the cam rollers 45 by which the gripper fingers 39 may be opened. As shown in Fig. 2 the cam 149 is in operative position and will function to open each set of grippers as it passes the cam.

Hand lever 132 carries a second stud 151 which pivotally supports one end of a link 152 the other end of which passes through nodule pin 153 and is adjustably clamped thereto by nuts 154. Nodule pin 153 is pivotally held by a lever 155 which is keyed to shaft 95. Secured on shaft 95 at positions corresponding to the spaces between grippers 39 are stripper fingers 156, any desired number of which may be provided, and two of

which are illustrated in the drawings. These fingers overlie the platform 74 and are arranged when in operative position to lie above a sheet held by the grippers 39 and below the shafts 40 and 42. They are also provided with abutments 157 against which the sheets may strike when released from the grippers and before settling onto platform 74.

The movement of shaft 95 in the clockwise direction is limited by an adjustable stop comprising a screw 158 in stud 159 which is fixed in frame 22.

The parts described above are arranged to occupy operative and inoperative positions shown respectively in Figs. 2 and 3.

If it is desired to move the parts from operative to inoperative position the hand lever 132 is moved counterclockwise until lever 155 strikes stop 158. This movement results in a partial rotation of shaft 135 and a corresponding shortening of lever and link connection 136, 138 sufficient to raise cam 149 out of engagement with any of the rollers 45, thereby permitting the sheets to be carried past platform 74. This movement of hand lever 132 simultaneously causes partial rotation of shaft 95 through the link and lever connection 152, 155 thereby lowering stripper fingers 156 below the sheet path. At the same time link 138 and lever 129 impart a partial rotation to large gear 128 which, acting through small gear 120 and shaft 118 causes counterclockwise rotation of drums 117 thereby winding up a part of the cables 114 and moving bar 108 and tapes 107 into the dotted line position of Fig. 4 where they support the sheets in their travel over the platform 74.

If it is desired to move the parts from inoperative to operative position the hand lever 132 is moved clockwise until abutment 139 of lever 136 strikes abutment 140 of link 138. This movement is transmitted in the reverse direction through the connections just mentioned to cause cam 149 to open grippers 39, stripper fingers 156 to strip the sheets from the grippers, and tapes 107 to be withdrawn away from sheet supporting position, as shown in Figs. 2 and 4.

When it is desired to remove a pile of delivered sheets from the machine without stopping the latter the operator moves hand lever 132 quickly to its Fig. 2 position choosing such a time in the press cycle as is required to cause the cam 149, stripper fingers 156 and tapes 107 to move into proper position after the leading edge of one sheet has passed the stripper fingers and before the leading edge of the next sheet reaches these fingers. Thereafter all subsequent sheets will be deposited upon the auxiliary platform 74. As soon as all sheets not deposited on platform 74 have been deposited in pile 56 the platform 62 is lowered to the floor and removed from the press in the usual way. An empty platform is then placed in the press and the cables 66, 67 are drawn up to raise the platform into sheet receiving position. When the main delivery is thus made ready for a new pile, the operator moves lever 132 quickly back to its Fig. 3 position again choosing a proper time in the cycle of the machine. Platform 74 is then withdrawn from the machine on its wheels 75, the accumulated sheets are removed, and the emptied platform replaced in position ready for use the next time a main pile is to be removed.

The main delivery gripper opening cam 59 preferably remains always in operative position as shown so that whenever a sheet is conveyed to

the high level of the conveyor it is deposited on the main platform. At other times the grippers merely open and close without depositing sheets.

This application is a continuation of applicant's original application, Ser. No. 412,390, filed Sept. 26, 1941.

The invention is not to be restricted to the details of construction shown but is defined by the following claims:

Having thus described my invention, I claim:

1. In a machine of the class described, a sheet conveyor comprising a plurality of sets of sheet grippers, a first delivery platform, means for opening said grippers to deposit sheets on said first delivery platform, a second delivery platform, and means for depositing sheets on said second delivery platform or permitting conveyance of sheets to said first delivery platform according to the desire of the press operator, said last-mentioned means comprising a cam for opening said grippers, sheet supporting means adapted to occupy a position over said second platform to support sheets in their passage thereover, and connections enabling said cam and sheet supporting means to be placed into or out of position for depositing sheets on said second platform.

2. In a machine of the class described, a sheet conveyor comprising a plurality of sets of sheet grippers, a first delivery platform, means for opening said grippers to deposit sheets on said first delivery platform, a second delivery platform, and means for depositing sheets on said second delivery platform or permitting conveyance of sheets to said first delivery platform according to the desire of the press operator, said last-mentioned means comprising a cam for opening said grippers, traveling tapes adapted to occupy a position over said second platform to support sheets in their passage thereover, and connections enabling said cam and tapes to be placed into or out of operative position for depositing sheets on said second platform.

3. In a machine of the class described, a sheet conveyor comprising a plurality of sets of sheet grippers, a first delivery platform, means for opening said grippers to deposit sheets on said first delivery platform, a second delivery platform, and means for depositing sheets on said second delivery platform or permitting conveyance of said sheets to said first delivery platform accord-

ing to the desire of the press operator, said last-mentioned means comprising a cam for opening said grippers, fingers for stripping sheets from said grippers, tapes adapted to occupy a position over said second platform to support sheets in their passage thereover, and a hand lever operatively connected to said cam, fingers and tapes for manually placing the same into and out of position for depositing sheets on said second platform.

4. In a machine of the class described, a sheet conveyor having upper and lower horizontal paths of travel, said conveyor comprising a plurality of sets of sheet grippers, a first delivery platform, means associated with said upper path for opening said grippers to deposit sheets on said first delivery platform, a second delivery platform, and means associated with said lower path for depositing sheets on said second delivery platform or permitting conveyance of sheets to said upper path according to the desire of the press operator, said last mentioned means comprising a cam for opening said grippers, fingers for stripping sheets from said grippers, tapes adapted to occupy a position over said second platform to support sheets in their passage thereover, and connections enabling said cam, fingers, and tapes to be placed into or out of operative condition simultaneously.

5. In a machine of the class described, a sheet conveyor having upper and lower horizontal paths of travel, said conveyor comprising a plurality of sets of sheet grippers, a first delivery platform, means associated with said upper path for opening said grippers to deposit sheets on said first delivery platform, a second delivery platform, and means associated with said lower path for depositing sheets on said second delivery platform or permitting conveyance of sheets to said upper path according to the desire of the press operator, said last mentioned means comprising a cam for opening said grippers, fingers for stripping sheets from said grippers, tapes adapted to occupy a position over said second platform to support sheets in their passage thereover, and a hand lever operatively connected to said cam, fingers and tapes for manually placing the same into and out of position for depositing sheets on said second platform.

ARTHUR B. WOODRUFF.
